UNITED STATES PATENT OFFICE.

JOHN WILLIAM JACKSON, OF EAST TAUNTON, MASSACHUSETTS.

SPARK PLUG.

Application filed September 30, 1921. Serial No. 594,353.

To all whom it may concern:

Be it known that I, JOHN W. JACKSON, a citizen of the United States, residing at East Taunton, in the county of Bristol and 5 State of Massachusetts, have invented a new and useful Spark Plug, of which the following is a specification.

This invention aims to provide a simple means whereby an operator by inspection, 10 can ascertain at any time whether or not a spark plug is working.

It is within the province of the disclosure to improve generally and to enhance the utility of devices of that type to which the 15 invention appertains.

With the above and other objects in view, which will appear as the description proceeds, the invention resides in the combination and arrangement of parts and in the 20 details of construction hereinafter described and claimed, it being understood that, within the scope of what is claimed, changes in the precise embodiment of the invention shown can be made without departing from 25 the spirit of the invention.

In the accompanying drawings:—

Figure 1 shows in elevation, a device constructed in accordance with the invention; Figure 2 is a longitudinal section on the 30 line 2—2 of Figure 1; Figure 3 is a fragmental section on the line 3—3 of Figure 2.

The spark plug forming the subject matter of this invention includes a body 1 provided at one end with threads 2 and 35 supplied at its outer end with threads 3, the body having, intermediate its ends, a wrench head 4. In the inner end of the body 1 there is a passage 5 communicating with an enlarged chamber 6 located in the upper end of the body. A shoulder 7 is formed at the place of juncture between the 40 passage 5 and the chamber 6.

The numeral 8 denotes the core of the plug, the core being received, in part, in the passage 5 and in the chamber 6. The core 8 has a shoulder 9 adapted to cooperate with the shoulder 7 of the body 1 of the plug. The core 8 is supplied with an outer shoulder 10. A packing gasket 12 surrounds the core 8 and rests on the shoulder 10. A first electrode 14 is located in the core 8 and is provided at its outer end with an enlargement 15, passing through a washer 16 mounted on the end of the core. 50

A binding nut 17 is threaded on the part 55 16 of the electrode 14 and cooperates with the washer 16. A second electrode 18 is located in the core 8. The inner end 19 of the electrode 18 preferably is extended toward the inner end of the first electrode 60 14. The outer end of the second electrode 18 is extended laterally, as shown at 20, in a direction substantially at right angles to the axis of the plug. In the side wall of the core 8, a transverse bore 21 is formed. 65 A packing disk 22 is seated in the inner end of the bore 21. The numeral 23 denotes a tubular guard, preferably made of glass. One end of the guard 23 is received in the bore 21 and abuts against the packing disk 70 22. The end 20 of the electrode 18 extends into the guard 23.

The numeral 24 marks a retainer including a flange 25 and a head 26, the retainer having wrench surfaces 27. The flange 25 75 of the retainer 24 is threaded on the part 3 of the body 1, the head 26 of the retainer engaging the packing gasket 12 and compressing the same, to secure a water tight joint, and compress the shoulder 9 of the 80 core 8 against the shoulder 7 of the body 1. The retainer 24 is provided with an ear 28 in which an adjustable terminal 29 is mounted. The terminal 29 preferably is in the form of a screw threaded into the ear 85 28. The screw or terminal 29 extends into the tubular guard 23, the outer end of the guard 23 being in close relation to the inner surface of the ear 28.

When the plug is working properly, a 90 spark will always occur between the end 20 of the electrode 18 and the terminal 29, and since this spark can be observed through the guard 23, the operator can ascertain at a glance, the condition of the plug. The 95 terminal 29 may be advanced or retracted so as to cooperate properly with the part 20 of the electrode 18. It is to be observed that the screw or terminal 29 enters the outer end of the guard 23 and constitutes a 100 closure therefor.

What is claimed is:—

In a device of the class described, a spark plug comprising a body; a core in the body and having a recess; a retainer threaded on the body and engaging the core; a tube extended between a portion of the retainer and the core and received in the recess of 105

the core; a screw threaded into said portion of the retainer and entering the tube; and an electrode in the core and extended into the tube, into jump spark relation with respect to the screw, and another electrode mounted in said core for cooperation with the first mentioned electrode.

In testimony that I claim the foregoing as my own, I have hereto affixed my signature in the presence of two witnesses.

JOHN WILLIAM JACKSON.
